SPRING DOOR LOCKER

Filed Oct. 11, 1924

Inventor:
Walter N. Vance

By Munsey, Clarke & Carpenter, Atts.

UNITED STATES PATENT OFFICE.

WALTER N. VANCE, OF CHICAGO HEIGHTS, ILLINOIS, ASSIGNOR, BY MESNE ASSIGNMENTS, TO LYON METAL PRODUCTS, INCORPORATED, OF AURORA, ILLINOIS, A CORPORATION OF ILLINOIS.

SPRING-DOOR LOCKER.

Application filed October 11, 1924. Serial No. 742,961.

My present invention relates to lockers, and particularly to an improvement in the mounting of the door, or doors of the locker, the primary object of the invention being to provide means for exerting spring tension upon the door in the direction of closing.

It is also an object to provide a spring door locker in which the spring may be readily positioned and will not add materially to the cost or difficulty of construction.

Numerous other objects and advantages of the invention will be apparent as it is better understood from the following description, which, taken in connection with the accompanying drawings, discloses a preferred embodiment thereof.

Referring to the drawings,

Figure 1 is a front elevation of a locker in which my invention is embodied;

Fig. 2 is a partial transverse section, taken substantially on the section line 2—2 in Fig. 1 and shown on an enlarged scale;

Fig. 3 is an enlarged fragmentary elevational view, taken from the inside of the locker; and

Fig. 4 is a transverse section, taken substantially upon the section line 4—4 in Fig. 3.

Upon said drawings, which illustrate the best manner in which I have contemplated applying the principles of my invention, the reference character 11 indicates generally a frame, which consists of corner angle members 12 and walls 13, the doors 14 being hinged at one side to the front flange 15 of one of the angle members 12.

The hinges 16 may be of any usual or preferred character and the doors are provided at the opposite side with a flange 17, adapted to abut against the exterior of the opposite angle member 12, a key-lock 18 being provided, as shown clearly in Fig. 2.

The flange 15, shown at the left in Fig. 1, is cut out at 19 to receive a coil spring 21, which is held in place by means of projections 22, extending into the ends of said spring. One end 23 of the spring is bent downwardly on the interior of the flange 15 and the opposite end 24 is extended through a retaining slot 25 in a flange 26 extending inwardly on the hinge side of the door.

Upon opening the door 14, the spring 21 is compressed by reason of the contact of the flange 26 with the extended portion 24 of said spring. The end 27 of said extended

portion 24 of the spring is curled and said portion is of such length that it will not be withdrawn from the door flange when the door is opened. In this manner, a yielding pressure is exerted upon the door in the direction of closing, so that it will remain normally in closed position and will be held in proper relationship to the frame.

It will be obvious that the spring may be inserted by merely compressing it in longitudinal direction, inserting it between the projections 22 and hinging the extended part 24 in the slot 25, which is open at the lower end thereof, as indicated at 28. An upwardly extending projection 29 is provided on the edge of the flange 15 at the inner side thereof, and serves to hold the downwardly turned end 23 of the spring in place.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A locker, comprising, a frame, a door, said frame and door having slotted portions, and a spring supported by the frame by interlocking engagement with integral portions thereof and having opposite ends engaging said slotted door and frame portions for yieldably resisting opening movement of the door.

2. A locker, comprising, a frame, a hinged door having a flange at the hinge side thereof, and a spring supported on the frame by interlocking engagement therewith having an end extending through the flange of the hinged door for urging said door toward a normal position.

3. A locker, comprising, a frame, a door hinged to said frame, and a coil spring supported in a cut-out part of the frame adjacent the hinge side of the door by interlocking engagement with integral portions of said frame, said spring having an end engaging said frame and another end engaging a cut-out portion of said door and arranged to yieldingly resist movement of the door.

4. A locker, comprising, a sheet metal

body formed with an opening, a sheet metal door, hinges connecting said door with said body to permit said door to swing, and a spring detachably connected with integral portions of the sheet metal body at its opening and having an end connected to said frame, said door being formed adjacent said opening with an inwardly extending flange having a slot, and an end of said spring engaging said slot.

5 5. A locker, comprising a frame, a door hinged to said frame, and a coil spring disposed in a cut-out part of the frame adjacent the hinge side of the door, and arranged to yieldingly resist the opening of the door, said frame having projections extending into the ends of said spring to hold the latter in place, and having a spring end retaining projection disposed adjacent the 10 spring.

15 6. The combination of two members hingedly mounted for relative movement, one said member being fixed and the other comprising a movable closure, and a coil spring for yieldably holding said members in a normal closed position, said movable member being slotted to receive a laterally extended end of the coil spring, and said fixed member being formed to provide a 20 spring seat in which the spring may be interlockingly engaged.

25 7. A spring closing device for hinged closures, comprising, two sheet metal members hingedly mounted for relative movement, one said member being fixed and the other comprising a movable closure, and a coil spring supported by integral portions of said fixed member and having a laterally extending end engaging a slotted portion of 30 said movable closure to urge it to a predetermined position with respect to said first member.

40 8. A hinged closure construction, comprising, a fixed part having integral portions formed to provide a spring retaining bear-

ing, a movable part having hinged engagement with said fixed part and having a slotted spring end retaining portion, and a spring having interlocking engagement in said spring retaining bearing and having ends engaging said fixed part and in said slotted portion of said movable part for yieldingly holding said parts in predetermined relative positions.

55 9. A hinged closure construction comprising a fixed frame having integral portions providing oppositely disposed spring retaining prongs adapted to engage within opposed ends of a coil spring to secure the same in place, a movable closure having hinged connection with said frame and having a slotted spring end engaging portion, and a spring supported on said frame and arranged for assembly upon said spring retaining prongs by compression along a longitudinal axis, said spring having a laterally extending end arranged to engage said slotted portion of the movable closure to yieldingly hold said parts in a predetermined relative position.

60 10. A locker comprising a sheet metal body having an aperture and a door frame adjacent said aperture, a door closing said aperture, said door having an inwardly extending flange and having hinged connection with said frame, the inwardly extending flange lying transversely of said door frame and adjacent thereto, said frame having a cut-out portion at its edge adjacent said inwardly extending flange and having a spring edge retaining slot formed therein adjacent said cut-out portion, said door flange having a spring end retaining slot formed therein opposite said cut-out portion, and a coil spring engaging said slotted frame and slotted door portions to permit said door to open against the yielding resistance of said spring.
